SPARKING PLUG FOR INTERNAL
COMBUSTION ENGINES

George Edward Woods-Humphrey, Chelsea, London, and Henry Leonard Hall, Streatham, London, England

Application March 23, 1933, Serial No. 662,973,
and in Great Britain April 19, 1932

4 Claims. (Cl. 123—169)

This invention relates to sparking plugs for the electrical ignition of combustible charges, and has for its object the production of a plug which will be less susceptible than existing types to short-circuiting arising from the bridging of the spark gap by carbon, oil, or other moisture and which need not be taken to pieces to permit of the same being cleaned. A further object is to so construct the plug that wear of the electrodes due to arcing and cleaning which limits the life of the plug, is reduced to a minimum.

A sparking plug constructed according to the invention is characterized by the following, that:—the head of the inner end of the central electrode is of approximately cylindro-conical form; the insulation thereon extends to the inner face of said head; the inner end of the body of the plug is furnished with a plurality of narrow fingers forming between same a plurality of correspondingly narrow ports through which said insulating material is directly exposed to and scavenged by the flames of combustion; and further a cylindrical annular space may be provided between the insulating material around the central electrode and the inner wall of the body, said space extending well back into the interior of the body; and the exposed end of the central electrode may be provided on its cylindrical portion with axially disposed projections, which in conjunction with the narrow fingers on the inner end of the body, provide a plurality of sparking edges.

In the accompanying drawing which illustrates this invention:—

Figure 1 is a view in elevation, one half being in section, of one form of the improved plug;

Figure 2 is a similar view of a modification.

Figure 3 is an end view of the inner end of the plug shown in Figure 2.

Figure 4 is a view in elevation of the inner end of a plug illustrating a modification, and,

Figure 5 is an end view thereof.

According to the embodiment illustrated in Figure 1, the inner end 1 of the body of the plug is bored to a relatively large diameter in order to leave an annular space 2 between the insulation material 3 which surrounds the central electrode 4 and the interior wall of the body, said space extending well back from the head of the plug into the body, that is, as shown in Figure 1, the annular space extends back to the shoulder 5 by means of which the central portion including the electrode 4 is clamped

into position by the sleeve nut 6, which permits said electrode to be adjusted or removed as desired. In order that the flames of combustion may reach the insulation material 3 behind the head 7 of the electrode 4, the extreme inner end 1 of the body is provided with a plain cylindrical portion beyond the threaded portion and this portion is castellated so as to provide a plurality of narrow fingers 8 which may be deformed towards the head 7 of the central electrode to form a sparking gap or gaps and between same a corresponding number of ports 15.

For the purpose of extending the life of the gap points the end 7 of the central electrode 70 may be formed as a short cylinder having axially disposed grooves 9 formed on its periphery so as to provide a plurality of projections or serrations which constitute the positive gap points, which may be brought into use simultaneously or successively, the negative gap points being formed by the fingers 8 on the plug body.

In the embodiment illustrated in Figures 2 and 3, the invention is shown applied to a long reach plug of the type in which the central electrode is not removably mounted in the body, otherwise the formation of the central electrode and negative gap points is substantially the same as described with reference to Figure 1, in which the tips of the projections on the central electrode extend only to within spark distance of the inner diameter of the fingers 8 on the body; said projections may, however, extend to the outer diameter of said fingers as shown in Figures 4 and 5. In this case the fingers 8 are arranged to enter grooves 10 provided in the end of the head of the central electrode, the projections 11 on said electrode thereby being disposed between the fingers 8.

What we claim is:—

1. A sparking plug for internal combustion engines in which the head of the inner end of the central electrode is of approximately cylindro-conical form, the insulating material thereon extending to the inner face of said head and in which the inner end of the body of the plug is furnished with a plurality of narrow fingers forming between same a plurality of correspondingly narrow ports through which said insulating material is directly exposed to and scavenged by the flames of combustion.

2. A sparking plug for internal combustion engines as claimed in claim 1, in which a cylindrical annular space is provided between the insulating material around the central electrode and

the inner wall of the body, said space extending well back from the inner end into the interior of the body.

3. A sparking plug for internal combustion engines as claimed in claim 1 in which the inner or exposed cylindro-conical end of the central electrode is provided with axially disposed projections on the periphery of the cylindrical portion extending only to within spark distance of 10 the inner diameter of the fingers on the body.

4. A sparking plug for internal combustion engines as claimed in claim 1 in which the inner or exposed cylindro-conical end of the central electrode is provided with axially disposed projections on the periphery of the cylindrical portion extending to the outer diameter of and between the fingers on the body. 80
